UNITED STATES PATENT OFFICE.

WILLIAM S. MILLS, OF BRIDGEPORT, CONNECTICUT.

KNITTING-MACHINE.

SPECIFICATION forming part of Letters Patent No. 687,380, dated November 26, 1901.

Application filed November 28, 1900. Serial No. 37,957. (No model.)

To all whom it may concern:

Be it known that I, WILLIAM S. MILLS, a citizen of the United States, and a resident of Bridgeport, in the county of Fairfield and State of Connecticut, have invented certain new and useful Improvements in Knitting-Machines, of which the following is a specification.

My invention, while relating to knitting-machines generally, has reference more particularly to that form thereof which are employed in the production of articles that are provided with appropriate welts and fashioned portions and are or may be ornamented with transversely-arranged stripes of different colors or materials. In an application for Letters Patent filed by me in the United States Patent Office March 27, 1900, Serial No. 10,835, I have shown and described a knitting-machine of this class in which the article being knit is continuously reproduced in a connected chain or series and the various operations necessary to the forming of the welt, the varying of the length of the loops, the ornamentation of the articles, and the bringing of the successive needles into operation for widening the same are all accomplished automatically and in the required order through the instrumentality of appropriate pattern mechanism. This construction, while efficient in accomplishing the results thus specified, has been found more or less deficient when applied in the production of certain articles, principally because of the fact that no means are provided for automatically withdrawing the needles from operation when the knitting of the narrower portions of the article is required, and as a consequence of this their withdrawal therefrom when those portions are to be produced can only be effected by hand. To supply this deficiency, therefore, and render the machine automatic in all its operations, as well as more simple and efficient in construction and operation, are the objects of my present invention.

To these ends the invention consists, first, in the peculiarities of construction of the needle-advancing cams and in the means whereby they are adjusted; second, in the means by which the necessary needles are automatically withdrawn from operation when the knitting of the narrower portions of the article is

required, and, third, in various other constructions and combinations of parts, all as will be hereinafter more fully described. 55

Referring to the accompanying drawings, which form a part of this specification, Figure 1 is a side elevation of a knitting-machine constructed in accordance with my invention, certain of the parts being broken away for convenience of illustration and others omitted; Fig. 2, a horizontal section thereof, taken in the line $y-y$ of Fig. 3, with certain of the parts similarly broken away for a like reason and the several pattern-chains also omitted; Fig. 3, an end elevation of the machine with certain of the parts likewise broken away for a similar reason; Fig. 4, a vertical transverse section taken in the plane xx in Fig. 2; Fig. 5, a front elevation of the front cam-carrying plate with the parts supported thereby; Fig. 6, an under side elevation of the rear cam-carrying plate, showing the needle-operating and needle-withdrawing cams, the needle-elevator, and the various other parts supported thereby; Fig. 7, a corresponding under side elevation of the front cam-carrying plate, showing in like manner the needle-operating and needle-withdrawing cams, the needle-elevator, and the several other parts supported by it; Fig. 8, a detached side elevation of the rear needle-elevating cams and their operating-slide, showing the relative position occupied by these cams when the slide is at the limit of its movement in one direction; Fig. 9, a similar detached side elevation of the same parts, showing the relative positions occupied by these cams when the slide is at the limit of its movement in the opposite direction; Fig. 10, a diagrammatic view 80 of the needle operating and withdrawing cams, the needle-supporting ledges, and the needles, showing the operation of the parts and the movements of needles during the knitting operation; Fig. 11, a similar view of the 85 same elements, showing the operation of the parts and the movements of the needles during the withdrawal of the end needles of the series in effecting the narrowing operation; Fig. 12, a transverse sectional detail, partly 90 in side elevation, of a portion of the front needle-bar and of certain of the parts co-operating therewith, taken in the plane xx of Fig. 1; Fig. 13, a detail plan of one of the

needle-elevators and of the latch, needles, and needle-keeper coöperating therewith, with the needles shown in transverse section; Fig. 14, a detail side elevation of the parts shown in Fig. 13, with the needle-elevator shown in transverse section and the keeper broken away; Fig. 15, a diagrammatic view showing the different positions occupied by certain stops with respect to their coöperating sliding bars in effecting the lowering and raising of the needle-withdrawing cams to respectively carry them into and remove them from operation when required; Fig. 16, a diagrammatic view showing the different positions occupied by certain other stops relative to their respective coöperating bars in accomplishing the required adjustments of the advancing and retracting cams of the needles of the front needle-bars to effect both the reciprocal operation of these needles and the lengthening and shortening of the loops produced by them; Figs. 17 and 18, diagrammatic views showing the different positions occupied by still other stops relative to their coöperating bars in accomplishing the required adjustment of the advancing-cams of the needles of the rear needle-bar, whereby those needles are not only reciprocated, but carried out of and brought back into operation at the required times; and Fig. 19, a detail isometric projection of one of the sliding bars for operating the advancing-cams of a slightly-modified construction, with the stops for coöperating therewith and portions of the arms in which these stops are supported.

In all the figures like letters are employed to designate corresponding parts.

A A' indicate the end frames or standards, upon which the various parts of the machine are arranged and supported and which, connected and held at the proper distance apart by appropriate tie rods or rails, (not shown,) have secured to their respective tops by screws a or otherwise the stands A^2 and A^3 , that support and carry a front rail C and a rear rail C' . These rails are preferably arranged in parallel relationship to each other and are either secured at their respective extremities to the upper ends of the stands by screws or otherwise or are formed integrally therewith, as desired, and it is in this latter form that I have shown them constructed.

D D' indicate the front and rear needle-bars, respectively, which are also arranged in parallel relationship to each other, with a narrow passage-way between them, through which the article or fabric being knit may be passed, and with their upper surfaces inclined upward and inward toward each other, as shown. As thus arranged they are respectively secured to the upper sides of the front and rear rails C and C' by screws c and are provided in their upper surfaces with the transversely-arranged grooves d for reception of the needles d' , which are reciprocated therein during the knitting operation. These needles are preferably of the latch

form and are provided with the usual operating-butts d^2 , projecting upwardly from their upper sides, with the grooves d for their reception so disposed with respect to one another that the grooves of one needle-bar are brought opposite the spaces between the grooves in the other, whereby in the operation of the machine the needles of the one bar may be reciprocated across and between the needles of the other bar, and vice versa. The needle-grooves d being thus disposed, the raising or tilting of the needles upward or downward therein are prevented, while they are yet left free to be longitudinally reciprocated by keepers d^3 and d^4 . To this end the keepers d^3 are severally provided with beveled upper edges d^5 , whereby to prevent injurious engagement of the latches of the needles therewith when such needles are withdrawn from operation, and as thus equipped they are severally located in suitable depressions formed near the upper edges of their respective needle-bars, in which positions they are rigidly secured by screws or otherwise. The keepers d^4 , on the other hand, are severally located near the lower outer edges of their respective needle-bars; but instead of being directly secured to the upper sides thereof, as is the case with the keepers d^3 , they are either formed integrally with or rigidly secured to the upper edges of the stop-bars d^6 , which are severally secured in an adjustable manner to the lower outer edges of the needle-bars by screws or otherwise, whereby to adjust and limit the backward movement of the needles when withdrawn from operation and at the same time afford a space between their inner faces and the outer edges of their respective needle-bars, into which the dirt and other foreign substance from the needle-grooves may be carried and from which it may be removed when desired.

Arranged in front of the front needle-bar D and in rear of the rear needle-bar D' are the respective guide-rails E E', which are secured at their opposite ends to the stands A^2 and A^3 or other convenient support by screws e or otherwise and are each provided in its inner edge with a groove e' for reception of a lip f of a saddle F , that is fitted to slide therein. This saddle extends across over both the front needle-bar D and rear needle-bar D' and in the operation of the machine is reciprocated back and forth longitudinally of the same. The means whereby this reciprocation is effected may be of various forms. In the drawings, however, I have shown it accomplished from the cross-shaft G and through the intervention of connecting-rods and appropriate sprocket wheels and chains, which are preferably located on opposite sides of the machine. To this end I make use of the supporting-rods A^4 and A^5 , which, fixedly secured in the stand A^3 , extend outward horizontally therefrom and support in the proper positions thereon the bearings g , g' , and g^2 for the various shafts. The

bearings g project downward from the under side of these supporting-bars and carry near their lower ends the cross-shaft G , which is provided on one of its ends with a hand-wheel 5 g^4 , that is equipped with a handle g^5 , and on its other end with a fast pulley g^6 and a loose pulley g^7 , through which handle and fast pulley the rotation of the shaft G may be effected either by hand or by power, as may be desired. The bearings g' and g^2 , on the other hand, project upwardly from the supporting-bars A^4 and A^5 at the proper distance apart and respectively support the shafts G' and G^2 , which are journaled therein, with the former shaft operatively connected with the shaft G through the intervention of spur-gears g^8 and g^9 and provided with sprocket-wheels g^{10} and g^{11} , and the latter shaft equipped with corresponding sprocket-wheels g^{12} and g^{13} , of which the former is connected with the sprocket-wheel g^{10} and the latter with the sprocket-wheel g^{11} by sprocket-chains g^{14} and g^{15} , respectively, as shown. The sprocket-chains g^{14} and g^{15} being thus supported and operated from the shaft G are connected with the saddle F through the intervention of connecting-rods g^{16} and g^{17} , of which the former is connected at one of its ends to the sprocket-chain g^{14} and at its other 25 to the front of the saddle, while the latter is similarly connected at one of its ends to the sprocket-chain g^{15} and at its other to the rear thereof. By this arrangement, as will be seen, not only will a smooth and easy reciprocating motion be imparted to the saddle when the shaft G is rotated, but in consequence of the power being communicated thereto both at its front and at its rear the length of the saddle itself may be very much 30 shortened.

Supported upon the under side of the saddle F over and in parallel relationship to the upper surfaces of the respective needle-bars D and D' are the cam-carrying plates H and H' , which support upon their under surfaces the cams by means of which the reciprocation of the needles to effect the knitting operation is accomplished. These cams may be modified in various ways. In my preferred form 45 of construction, however, they consist of a pair of advancing-cams I and I' and a retracting-cam I^2 for the needles of each of the needle-bars, of which the advancing-cams I and I' are preferably constructed of a general 50 trapezoidal form and the retracting-cams of a general V form, with the walls on opposite sides of its lower angular portion recessed, as shown. As thus constructed these cams are supported upon the under surfaces of their 55 respective carrying-plates H and H' , with the advancing-cams arranged on opposite sides of their coöoperating retracting-cams, as shown in Figs. 6 and 7, whereby to engage with the butts of their respective needles in being carried over them to advance such needles before their butts are brought into engagement 60 with their coöoperating retracting-cams to be

retracted by them. In order, therefore, that the leading advancing-cam of each of the carrying-plates may be brought into proper position to engage with the butts of its respective needles to advance the latter as it is carried over them in whichever direction the saddle F may be traveling and its following companion advancing-cam so disposed as not 70 to engage therewith, these advancing-cams instead of being fixedly secured to their respective carrying-plates are severally secured to the inner ends of the short shafts i , which are journaled in their respective carrying-plates and are provided at their outer ends with crank-arms i' . As thus supported the rotation of these cams about the axes of their supporting-shafts may be effected through the medium of the crank-arms i' , whereby to 75 bring them into and carry them out of operative relationship with respect to the butts of their appropriate needles, as may be desired. When in their operative positions, the advancing-cams will be so turned as to bring 80 their upper operative surfaces in an upwardly-inclined relationship with respect to the paths of their travel and the butts of the needles to be operated by them, as shown by the cam I' in Figs. 6, 7, 10, and 11. On the 85 other hand, when carried into their inoperative positions their upper operative surfaces, with the remaining portions of these cams, will be disposed in parallel relationship to their respective paths of travel, as shown by 90 the cams I in those figures, and in that relationship they will be wholly above and removed from contact with the butts of their respective needles as they are carried over them. With a view, therefore, to so operating 95 these advancing-cams that when the leading cam of each of the carrying-plates is brought into operative relationship with respect to the butts of its appropriate needles its following companion cam shall be carried into an inoperative position with respect 100 thereto, and vice versa, I make use of the bars I^3 and I^4 , of which the former is employed in connection with the cams for operating the needles of the front needle-bar and the latter 105 in connection with the cams for operating the needles of the rear needle-bar. As thus employed these bars are fitted to slide longitudinally in suitably-formed seats in the respective carrying-plates H and H' and are 110 connected with the crank-arms i' of their respective cams to impart to the latter the required movement as the bars are slid back and forth in their carrying-seats. The means whereby this connection is effected may be 115 of various forms. I prefer, however, to employ slots and pins for the purpose, and to that end I provide each of the bars with slots i^2 and i^3 , which are constructed with oppositely-arranged diagonal middle portions and 120 longitudinally-extending ends and severally engage with pins i^4 , extending outward from the crank-arms i' . By this arrangement, as 125 will be seen, when either of the bars is moved

to the limit of its movement in one direction—as shown, for instance, in Fig. 7—the pin i^4 projecting from the crank-arm i' of the advancing-cam I will be carried up into the upper extremity of the slot i^2 and the cam I thereupon brought into an inoperative position, while the pin i^4 projecting from the crank of the cam I' will be similarly carried down into the lower extremity of the slot i^3 and that cam thereby carried into operative position. On the other hand, when this bar is moved in an opposite direction then the position of the pins will be reversed and the pin i^4 of the cam I will be carried down into the lower extremity of the slot i^2 and that cam thereby brought into operative position, while the pin i^4 of the cam I' will in like manner be carried upward to the upper extremity of the slot i^3 and that cam thereupon carried into an inoperative position, as shown by dotted lines of that figure, and so on in alternation, the sliding of the bar in one and then in the other direction bringing one and then the other of the cams I and I' into and carrying them out of operation in that order and positively holding them in those positions. When the knitting of the body portion of an article or fabric is being effected, the advancing-cams of the needles of both needle-bars will be required, and their positions will be changed, as above explained, at every back-and-forth reciprocation of the same, whereby the needles of both needle-bars may be rendered active and coöperate in the production of every course. On the other hand, when the knitting of a welt or other similar portion is being accomplished then as the needles of but a single needle-bar are required the advancing-cams of the needles of that particular needle-bar will alone remain in action, and the advancing-cams of the needles of the other needle-bar will be withdrawn therefrom. In some instances the advancing-cams thus withdrawn from action may be those of the needles of the front needle-bar, while the advancing-cams of the needles of the rear needle-bar may remain in action, and in these cases the welt will be knit by the needles of the rear needle-bar. I prefer, however, to withdraw the advancing-cams of the needles of the rear needle-bar from operation and to knit the welt or other similar portion with the needles of the front needle-bar. In order, therefore, to effect the withdrawal of the advancing-cams of the needles of the rear needle-bar from operation when the knitting of a welt or other similar portion is required and return them into operation when it is completed, the slot i^2 in the bar I^4 is constructed with the diagonally-arranged portion i^5 , which extends upwardly from its lower end and is provided at its upper extremity with a longitudinally-extending portion, while the slot i^3 therein is constructed with an elongated portion i^6 , which extends from its upper extremity longitudinally of the bar, as shown more clearly

in Figs. 8 and 9. As thus constructed whenever the extended portions i^5 and i^6 of the slots i^2 and i^3 are brought into such relationship with respect to the pins i^4 in the crank-arms i' of the respective cams I and I' that these pins rest in the outer extremities thereof by moving the bar I^4 in the required direction these cams will both be brought into the positions shown in Fig. 9, in which they will lie in parallel relationship with respect to their path of travel and both will be inoperative. On the other hand, when the bar I^4 is moved in an opposite direction until the pins leave the extended portions i^5 and i^6 and enter the slots i^2 and i^3 proper then the cam I' will be brought into operation and will with its companion cam I be successively brought into and carried out of operation whenever this bar is so reciprocated that only the slots i^2 and i^3 proper are caused to travel back and forth over their respective pins i^4 . Thus through the bar I^4 and the slots i^2 and i^3 and their respective extended portions i^5 and i^6 not only are the advancing-cams I and I' brought into and carried out of operation in the required order to effect the proper reciprocation of their appropriate needles, but these cams are retired from and returned into operation as desired and locked in those positions. While the advancing-cams of the needles of both the needle-bars are thus pivotally secured to their respective carrying-plates H and H', the retracting-cams I^2 of the needles of both the needle-bars may be either fixedly or adjustably secured to theirs, or one of the cams may be fixedly secured to one of the plates and the other adjustably secured to the other plate thereof. I prefer, however, this last-mentioned arrangement, and in conformity thereto I secure the retracting-cam I^2 of the needles of the rear needle-bar fixedly to the carrying-plate H' and secure the retracting-cam I^2 of the needles of the front needle-bar adjustably to the carrying-plate H, as shown in Figs. 6 and 7. For securing the cam I^2 to the plate H', I make use of a screw h , which, extending through a suitable aperture formed in the cam, engages at its end with an appropriately-threaded orifice formed in the plate, while for adjustably securing the retracting-cam of the needles of the front needle-bar to the carrying-plate H, I employ the carrier h' , which, fitted to slide transversely of that plate in suitable guideways h^2 , formed on or secured to its under side, has the cam I^2 secured to its face by a screw h^3 , that extends in like manner through a suitable aperture formed in the cam and similarly engages at its end with an appropriately-threaded orifice formed in the carrier h' . In most instances the screws h and h^3 will be found sufficient for securing the respective rear and front retracting-cams I^2 to the carrying-plate H' and carrier h' . In order, however, to more fully insure of their being held in those positions without displacement, as well as to aid in their accurate location upon those parts, I

sometimes find it expedient to severally provide them with flanges or ribs h^4 on their backs, which respectively enter correspondingly-shaped grooved or seats formed in the 5 carrying-plates and carrier, and also with screws h^5 , that are threaded in the respective upper edges of the carrying-plate and carrier and engage by the overhanging portions of their heads with the upper edges of their respective 10 cams, as shown. As thus disposed the retracting-cam of the needles of the rear needle-bar is fixedly and immovably held with respect to its carrying-plate H' , while the retracting-cam of the needles of the front 15 needle-bar may be adjusted transversely with respect to its carrying-plate H to lengthen or shorten the loops produced by those needles, and thereby thicken or thin the article or fabric by simply sliding the carrier 20 h' in one or the other direction in the guideways h^2 , as the requirements of the particular adjustment may demand. For sliding this carrier in its guideways when required various means may be adopted. I prefer, however, 25 to employ for this purpose a crank or an eccentric h^6 , which, engaging with a slot h^7 in an ear h^8 , extending upward from the carrier, is formed on or secured to the inner end of a short shaft h^9 , that is rotatively 30 mounted in a suitable bearing formed in the upper edge of the carrying-plate H , in which it is held by a cap h^{10} through the intervention of appropriate screws h^{11} . With the crank or eccentric h^6 engaging with the slot 35 in the ear h^8 , as thus explained, the sliding of the carrier downward or upward to lengthen or shorten the loops being produced or otherwise may be accomplished by oscillating the shaft h^9 in the required direction. To effect 40 this oscillation, I preferably make use of the crank-arm h^{12} , which is fixedly secured to the outer extremity of the shaft h^9 and has jointed to its own free end by a pivot h^{13} a bar H^2 . By these means, as will be apparent, the oscillation 45 of the shaft in the required direction may be effected by simply moving the bar H^2 longitudinally forward or backward, as the requirements of the oscillation may demand, and in order to maintain this bar in parallel 50 relationship to the path of its travel in whatever position it may be thus moved I make use of a link h^{14} , which, constructed of the same length as the crank-arm h^{12} , is pivoted at one of its ends to the carrying-plate 55 H at some distance from the crank-arm and at its other end to such bar, as shown.

With the various cams arranged and operating as above described the advancing and retracting cams of the needles of both needle-bars will be brought into operation when the 60 knitting of the body of the article or fabric is being effected, and the needles of both needle-bars will then be successively advanced and refracted from one end of the series to the other at each forward-and-backward 65 movement thereof and the knitting accom-

plished by the conjoint action of the needles of both needle-bars. On the other hand, when the advancing-cams of the needles of the rear needle-bar are withdrawn from operation 70 then the needles of the front needle-bar will be thus actuated alone during each back-and-forth movement of the cams, while the needles of the rear needle-bar will remain inoperative in a retracted position, with the result that the knitting will be accomplished by the operation of the needles of the front needle-bar alone, and thus by simply retiring from and bringing back into operation the advancing-cams of the needles of the rear 75 needle-bar a fabric may be produced by the operation of the needles of either one needle-bar or of both needle-bars, as desired.

When in the position for advancement and retraction by the cams I , I' , and I^2 , to effect 80 the knitting operation the needles d' may be held at the proper height in their supporting-grooves d to bring their operating-butts d^2 in position for engagement with the lower portion of the operating-surfaces of the advancing-cams I and I' , as shown at the right in Figs. 10 and 11, by the strain of the loops of the fabric upon them or the friction between themselves and their respective grooves. When, on the other hand, any of these needles 85 are withdrawn from operation during the knitting of the article or fabric, as they are, for instance, when the narrowing operation is being performed or the narrower portions of it are being knit, then these latter 90 needles rest lower down in their supporting-grooves, with their operating-butts d^2 below their respective advancing-cams, as shown at the left in Fig. 11, and in order to insure of their maintenance in one or the other of 95 the positions to which they may be thus adjusted at all times except when being carried from one to the other to effect the narrowing or widening operation I construct each of 100 these needles with an elongated tail d^7 , which 105 is provided near its lower end with a second butt d^8 , and employ in connection with them supporting-edges J . These edges are preferably constructed with parallel upper and under edges that terminate at their outer 110 ends in downwardly and upwardly inclined surfaces, respectively, and as thus constructed they are preferably secured some distance below the advancing and retracting cams of 115 each of the carrying-plates by suitable screws j and appropriate dowel-pins, if desired, with a space between the inner ends of the edges of each of the carrying-plates. As thus arranged they engage with the butts d^8 of such of the needles d' as are carried out of and 120 brought back into operation during the narrowing and widening of the article or fabric being produced and serve in the back-and-forth movements of their respective carrying-plates to raise and lower such of these needles as may have been accidentally lowered 125 or raised to any slight extent from the re-

spective positions to which they may have been adjusted and insure of their retention therein.

For carrying the needles which are employed in the narrowing and widening operations from their upper or operative position to the lower or inoperative position when the narrowing operation is effected various means may be employed. I prefer, however, to accomplish that result through the intervention of withdrawing-cams K, of which there is one for the needles of each of the needle-bars. These cams are preferably constructed of the form shown in Figs. 6, 7, 10, and 11 and are supported upon the under side of the carrying-plates H and H' below their respective retracting-cams I² in proper position to engage with the butts d⁸ of their coöperating needles when brought into proper relationship to them. Instead, however, of being fixedly secured to the under side of their respective carrying-plates these withdrawing-cams are severally secured by screws k or otherwise to the lower ends of carrying-bars k', which are fitted to slide perpendicularly through those plates in suitable orifices k³, formed in them, whereby to permit of the cams being moved downward toward and upward from their coöperating needles to bring such cams into and carry them out of engagement with the butts d⁸, as required. In their inoperative position, as when the needles are employed in the knitting and widening operation, these cams will be raised above the butts d⁸ of the needles with which they respectively coöperate, as shown in Fig. 4, and in these positions they will not engage with those butts when carried over them. On the other hand, when the narrowing operation is to be performed then these cams will be lowered until they are brought into relationship to those butts, as shown in Fig. 12, when in being carried over them the cams will engage with the butts and retire such of the needles from operation as are to be withdrawn therefrom. In order, therefore, to effect the raising and lowering of these cams when required, I make use of the bars K' and K², which, mounted to slide in suitable guide-ways formed in the stand k², that extends upwardly from the respective carrying-plates H and H', are severally provided with slots k⁴, that are constructed with diagonally-arranged middle portions and longitudinally-extending ends and engage with appropriate pins k⁵, with which the respective carrying-bars k' are severally provided. As thus arranged the raising and lowering of these withdrawing-cams may be effected by simply sliding their carrying-bars K' and K² in one and the other direction, and in order to permit of the upward movement of these cams whereby to bring them above the butts of the needles the respective carrying-plates H and H' are severally provided on their under sides with suitably-recessed portions k⁶, into which these cams may be withdrawn, while

to insure of the needles being withdrawn when the narrowing operation is performed before the butts d² enter the recesses in the 70 retracting-cams I² and engage with the yarn to form new loops the upper operating-corners k⁶ of these withdrawing-cams are so disposed with respect to those recesses that they engage with the butts d⁸ of the needles before their butts d² enter them, and thereby cause their respective needles to be retracted before the yarn is carried across their hooks, as shown in Fig. 11. By these means, therefore, as will be seen, I provide for the withdrawal of the needles that are to be carried out of operation when the narrowing of the article or fabric is to be effected before they engage the yarn for the production of new loops, while leaving those needles that are to 85 continue the knitting operation and are unprovided with butts d⁸ to continue in action undisturbed.

For carrying the needles from their inoperative into their operative position to effect the 90 widening of the fabric or otherwise, on the other hand, I make use of a needle-elevator L for the needles of each of the needle-bars. These elevators are severally constructed in the form of arms and are rotatively mounted 95 upon short shafts or studs l, that are respectively supported upon the cam-carrying plates H and H' above and in parallel relationship to the upper sides of these plates by the stands k² and the coöperating plates l², with the inner ends of the arms extending through flattened V-shaped orifices l³, formed in their respective carrying-plates directly below the retracting-cams I². As thus arranged these elevators are each adapted to be swung back 100 and forth upon its supporting shaft or stud l by the action of the butts d⁸ of the needles upon its end, and in order to provide for the engagement of these butts therewith this end is constructed with a head l⁴, which in its normal operative position is held in line with those butts, and is provided on its opposite side with notches l⁵, with one and the other of which these butts engage as the elevator is carried back and forth over them with the 105 cams in the operation of the machine. When the widening of the article or fabric being produced and the return of the needles from their inoperative to their operative position is not required, the elevators are held with 110 the heads upon their free ends near the upper edges of the orifices l³ in their respective carrying-plates H and H' above the butts d⁸ of the needles, then in an inoperative position, as shown in Fig. 6. When, on the other hand, the widening operation is to be performed and one or more of the needles of each of the needle-bars is or are to be carried from their inoperative to their operative positions, the elevators L are severally lowered until their heads rest in the apexes of the lower portions of the V-shaped orifices l³ in their respective carrying-plates H and H' upon the surface d⁶ of the keeper d⁴, as shown by dotted lines at

the right in Fig. 14. In these positions the notches l^5 in their heads will be severally brought into proper relationship for engagement with the butts of the needles of their respective needle-bars, and, in order to provide for the raising and lowering of these elevators from one to the other of these positions, and the automatic return of their heads to the apexes in the lower edges of those orifices 5 when disengaged from the butts of the needles, without interfering with their freedom of vibration back and forth upon their respective shafts or studs l , each elevator is provided with a hub l^6 upon its upper side and 10 is fitted to oscillate and slide longitudinally upon its respective supporting shaft or stud, being normally pressed downward along the same with its end in the apex of its respective V-shaped orifice l^8 , upon the surface d^6 of the 15 keeper d^4 in proper position for engagement with the butts d^8 of its appropriate needles by a coil-spring l^7 , which, surrounding its supporting shaft or stud, bears at one end against the plate l^2 on the stand k^2 and at the other 20 against the shoulder l^8 on the hub l^6 . The parts being arranged as thus described, when the elevators are in their lowest positions and the needle-operating cams are moved in one direction over the needles d' by the saddle F 25 the butt d^8 of the first inoperative needle of each of the needle-bars on the opposite edge of the series of operative needles will engage with the foremost notch l^5 in the head of its respective elevator as this elevator is brought 30 opposite thereto and such elevator swung backward on its supporting shaft or stud l as the movement of the cams and saddle continues. As a result of this swinging movement of the elevator on its supporting shaft or stud 35 l the under side of its end will ride up the inclined portion of the inner edge of the V-shaped orifice l^8 in its respective carrying-plate H or H' , thereby raising the elevator as a whole and carrying with it the needles with whose butt 40 d^8 its notch l^5 is engaged. This duplex movement of the elevator will continue until its head in its curvilinear travel may have been carried back into the orifice l^8 away from the butt d^8 of the needle, which will then be engaged 45 by the supporting-ledge J , that is following and which is provided at its inner end with the upwardly-inclined surface j' , whereby to aid in that engagement, and thereby insure of the needle being raised to the proper 50 elevation to permit of its butt d^2 being engaged by the advancing-cam I or I' in its next reciprocation in the opposite direction. The elevator having been thus swung backward by the action of the butt d^8 of the needle 55 60 thereon will when released therefrom be forced downward by the spring l^7 in the orifice l^8 , and by the action of the inclined side of the latter upon it during this movement it will be swung forward, the result of which 65 and of its forward movement with the cam will be to carry its end forward upon its higher surface d^9 of the keeper d^4 , as shown by dot-

ted lines at the left of Fig. 14. In this position it will travel on its outward and return movement until in its latter movement it 70 passes back over the butts d^8 of the inoperative needles on that particular edge of the operative series, when it will be forced downward upon the lower surface d^6 of the keeper d^4 by the spring l^7 , ready for engagement with 75 the butt of the needle on the opposite edge of the series, when the same operation will be repeated, and so on, the higher surface d^9 serving to hold the elevator from engagement with the butts d^8 of any of the needles but the 80 proper ones, and the lower surfaces d^6 serving to properly guide it and insure of its engagement with the latter as it is carried forward toward them in the operation of the machine. When, on the other hand, the needle-operating cams are moved in the opposite 85 direction by the saddle F , then the notch l^5 on the opposite side of the head of each elevator will be brought into engagement with the butt d^8 of the first needle of its respective 90 needle-bar on the opposite edge of the series of the operative needles, and thereby the elevator swung backward in an opposite direction and similarly raised, carrying with it that needle-butt and delivering it to the 95 upwardly-inclined surface j' of the other supporting-ledge J for co-operation with the advancing and retracting cams at their next forward movement in a reverse direction, and so on, each elevator at each back-and-forth 100 movement of the needle-operating cams engaging with and carrying into operation a single needle so long as the widening operation is continued. The widening operation having been completed, the elevators will be 105 raised to the upper edges of the orifices in their respective carrying-plates H and H' and there held until the widening operation is to be again performed, when they will be lowered into operation, as before explained, and 110 so on.

With the heads l^4 of the elevators sliding over the butts d^8 of their respective needles in passing from the surface d^9 of the keeper d^4 to the butts of the next needle to be brought 115 into operation by them these elevators will be caused by the friction between their respective heads and those butts to swing backward somewhat, as shown in Fig. 13, if no provision is made to prevent it instead of maintaining 120 a perpendicular relationship with respect to their carrying-plates, and as a consequence thereof when the number of needles of each needle-bar that remain in operation is small the heads of these elevators sometimes fail to 125 pass downward properly into the narrow spaces between the inner inoperative needles of their respective needle-bars and engage with the needles to be next carried into operation. To obviate this and provide for the holding of the elevators perpendicularly to their respective carrying-plates, or approximately so, in approaching these narrow spaces, I make 130 use of the latches L' , which are pivoted at one

of their ends to their appropriate carrying-plates H and H' by pivots l^0 and are severally provided on their under edges, near their opposite ends, with notches l^{10} for engagement 5 with their respective elevators when the latter are brought into relationship to them, Figs. 1, 5, and 14. As thus arranged, whenever either of the elevators has carried a needle of its respective needle-bar into operation 10 and has itself been returned to its normal position by its spring l^7 it will be engaged by the notch l^{10} of its respective latch L', which will be forced down over it by a spring l^{11} . In this position the elevator will be held until 15 it is brought over the space between the inoperative needles of its respective needle-bar, when it will be forced downward into that space by the action of its spring l^7 and its engagement with the next needle to be carried out of operation insured. In thus 20 moving down into the space between the inoperative needles the elevator will be followed by its appropriate latch L' until its head l^4 has entered that space, when the further downward movement of the latch will be 25 arrested by a pin l^{12} , extending outward from its respective carrying-plate, as shown in full lines in Fig. 5, and the elevator then left free to swing backward and travel upward along the inclined edge of the V-shaped orifice after 30 engaging with the butt d^8 of the next needle. Immediately, however, it commences to travel upward along this inclined edge and is swung slightly to one side it will contact with the 35 under edge of this latch at one side or the other of the notch l^{10} therein, and in its further upward movement it will carry with it the free end of such latch, which resting upon and moving upwardly and downwardly with 40 it, as shown by dotted lines in Fig. 5, will in turn engage by its notch with the elevator whenever the latter is in its normal position upon the butts d^8 of the needles or in perpendicular relationship to its respective carrying-plate above them. By this arrangement, 45 as will be seen, provision is made for positively holding the elevators in proper positions for entry into the spaces between the inoperative needles of their respective needle-bars, and thereby obviating the trailing of those parts as a result of the friction between them and the butts of their appropriate needles.

Sustained above the needle-bars D and D' 55 in suitable stands M, that are secured to the guide-rails E E' near their ends by screws m , are the guide-rods M' M', upon which the yarn-carriers N N are fitted to slide. In practice there will preferably be as many of these 60 yarn-carriers as there are kinds and colors of yarn to be incorporated into the fabric or article to be produced. In the present instance, however, I have shown but two, and each of these is preferably constructed with 65 a thin springy depending body portion n , having its lower end n' thickened and provided with an eye n^2 for the passage of the yarn

therethrough and is secured near its upper end to a head-like portion n^3 , which is fitted to slide upon its respective guide-rod M'. As 70 thus arranged the eyes n^2 of both yarn-carriers are brought approximately over the line of crossing of the needles as the latter are reciprocated in the operation of the machine, and in order to maintain each of them in this 75 position during the time it is being separately carried back and forth over the same the body n of the carrier in which it is employed extends upwardly from its head-like portion n^3 and engages at its upper extremity through 80 the intervention of a sleeve n^4 , to which it is secured with a second guide-rod M², which is supported above and in parallel relationship to its respective guide-rod M' in suitable stands n^5 , extending upward from the latter 85 rod, as shown. The eyes n^2 of both the yarn-carriers N being maintained in approximately the line of crossing of the needles d' are separately brought into action and operated in the required order to present their respective 90 yarns to the needles for incorporation into the fabric or article at the points demanded and are adapted to pass each other as they are successively brought into operation and reciprocated past each other by the springy 95 construction of their depending body portions n , which permits of the eyes being carried outward laterally as the thickened lower ends n' of the carriers arrive opposite each other, and which, to permit of this lateral action 100 being effected, have the ends of their inner contacting sides rounded off or beveled back to aid in the passage of the one by the other when brought opposite thereto. For imparting a back-and-forth reciprocating movement 105 of these yarn-carriers N N, I make use of a locking-lever O, which is preferably constructed in the form of a bell-crank, with an upwardly-extending arm o and a laterally-projecting arm o' , and is pivoted by a pivot o^2 110 to the upper end of a stand P, that is secured to and extends upwardly from the saddle F, whereby to move with the latter as it travels back and forth over the needles d' in the operation of the machine. As thus 115 constructed and arranged the upwardly-extending arm o of this locking-lever co-operates with studs O' O', which are severally secured to and project outwardly from the head-like portions n^3 of the carriers N in parallel relationship to each other and are severally provided with recesses o^3 , with one or the other of which the upper end of the upwardly-extending arm o of the locking-lever 125 engages as this lever is vibrated back and forth on its pivot at the upper end of its carrying-stand P. By this arrangement, as will be seen, the movement of the one or the other of the carriers N with the saddle F to lay its yarn in the hooks of the needles may 130 be effected, while the other is left inoperative by simply engaging the upper end of the upwardly-extending arm o of the locking-lever O with the recess o^3 in its appropriate stud O',

which may be accomplished by vibrating the locking-lever in the proper direction on its carrying-stand, when the two will be locked together and their movement in unison insured, 5 and in order to provide for the movement of each of the yarn-carriers in rear of the needle-operating cams, in whichever of the two directions the latter may be moving, the recess o^3 in its respective stud O' instead of being constructed of a length to just receive the upper end of the upwardly-extending arm o of the locking-lever O is constructed of a length sufficient to permit of the cams moving to the required distance in the one or the 10 other direction to bring them into the proper relative position with respect to the carrier before the upper end of the upwardly-extending arm of the locking-lever is brought into contact with the shoulders or walls o^4 of the 15 recess o^3 of its appropriate stud O' to move such carrier, when the two will be moved together and their relation thereafter maintained throughout the traverse. The yarn-carriers being constructed and operated as 20 thus explained, the yarns may be conducted from suitable bobbins or spools (not shown) to the eyes n^2 of their respective carriers through suitable guiding, taking-up, and clamping devices; but these, with the devices 25 30 for taking up the article or fabric as rapidly as produced, form no part of my present invention and are or may be the same as the corresponding parts shown and described in my before-mentioned application for Letters 35 Patent and require no further description herein.

With the parts constructed and arranged as above described the longitudinal movements of the bars I⁴, K', K², and H² may be 40 controlled and the needle-elevators and yarn-guides brought into and carried out of operation at the appropriate times and in the required order by any of the well-known form of pattern mechanisms that are capable of 45 those results. I prefer, however, to employ for this purpose the pattern-chains S, S', S², S³, S⁴, S⁵, and S⁶, which are severally constructed with appropriate high and low pattern-surfaces s and s', that are arranged upon 50 them in the required order, and to support such chains upon a suitably-constructed sprocket-wheel or barrel s², which is mounted upon a stud s⁸, that is secured to and extends outward from the stand A². The pattern- 55 chains being thus supported and arranged are moved progressively forward to bring their respective high and low pattern-surfaces into operative positions by a step-by-step movement from their sprocket-wheel or barrel s², 60 which is intermittently rotated from an inclined surface s⁴, secured to the under side of the saddle F, near the front edge of the latter. To permit of this rotation being effected therefrom, I preferably make use of a rod or 65 bar s⁵, which is fitted to slide vertically in a suitable hanger s⁶, that is secured to and depends from the under side of the rail E, with

the upper end of this rod or bar so disposed with respect to the line of travel of the inclined surface that it is struck and depressed by the latter as it is carried over the same by the saddle in the operation of the machine. As thus arranged the lower end of this rod or bar rests upon the upper side of an arm s⁷, which is fixedly secured to one end of a shaft S⁷, which, rotatively mounted in the stand A² and the hanger s⁸, also depending from the under side of the rail E, is equipped at its opposite end with a second arm s⁹, to the upper end of which is loosely jointed a pawl s¹⁰, that 75 engages with a ratchet-wheel s¹¹, which is secured to the sprocket-wheel or barrel s². On the other hand, to withdraw the pawl after it has been moved forward to rotate the sprocket-wheel or barrel and return the rod or bar s⁵ to its normal position ready for contact with the inclined surface s⁴ as it is carried over the same I make use of a spring s¹², which, coiled around the shaft S⁷, is fixedly secured at one end thereto and at the 80 other to the stand A² or other convenient part by a screw or pin s¹³. By this arrangement, as will be seen, the forward rotation of the sprocket-wheel or barrel s² the distance of one tooth will be positively effected at each 85 forward and backward reciprocation of the saddle F, which rotation will be of sufficient extent to bring the required high or low pattern-surfaces on the pattern-chains into operative positions, and in order to prevent it 90 from exceeding that limit by the momentum imparted to it by the pawl s¹⁰ as the latter is reciprocated forward to rotate it or of being moved backward therefrom by accident or otherwise I make use of appropriate restraining devices—as, for instance, a brake s¹⁴, which, provided with a stem s¹⁵ and supported from the stand A², through the intervention of a bracket s¹⁶, in which its stem is fitted to slide, is pressed against the periphery of the wheel or barrel s² by a spring s¹⁷, 95 100 105 110 115 120 125 130 135 as shown.

The pattern-chain S⁴ is employed for controlling the movements of the bar I⁴, by means of which the advancing-cams I and I' of the needles of the rear needle-bar D' are brought into and carried out of operation successively and together as the requirements of the article or fabric being produced demand. To this end the shaft I⁵ is made use of, which is 115 journaled in the stands A² and A³ and which, provided with an arm i⁷, that rests at its outer free end upon the pattern-chain through the intervention of a roll i⁸, is equipped near its opposite ends with upwardly-extending arms i⁹ and i¹⁰, of which the former is provided near its upper end with a stop i¹¹, while the latter is similarly provided near its upper end with a pair of these stops i¹² and i¹³. These several stops being thus supported are preferably constructed in the form of inwardly-projecting pins and are so disposed as to bring the stops i¹¹ and i¹² into axial coincidence and the stop i¹³, which is constructed of somewhat greater

length, to one side of the latter. As thus constructed and arranged these stops coöperate with the bar I^4 and serve to move it longitudinally in one and the other direction as one and the other of its ends are respectively brought into contact with their appropriate stops by the reciprocation of the bar back and forth with the saddle F. When the roll i^8 in the outer free end of the arm i^7 is resting upon one of the low pattern-surfaces s' , the stops i^{11} and i^{12} will be brought into line with the bar I^4 and the stop i^{13} will be carried to one side thereof, as shown in Fig. 18. With the stops disposed in these positions the opposite ends of the bar I^4 will be alternately brought into contact with their respective stops i^{11} and i^{12} as the bar is reciprocated back and forth with the saddle F and the bar thereby moved back and forth longitudinally the length of the slots i^2 and i^3 , with the consequent effect of bringing the advancing-cam that is to lead in the next reciprocation into operative position, as shown at the right in Fig. 8, and carrying its companion advancing-cam into an inoperative position, as shown at the left in that figure, and so on, the bar I^4 being moved in one and the other direction as its respective ends are brought into contact with the stops i^{11} and i^{12} and the advancing-cams there-by alternately brought into and carried out of operation so long as the reciprocation of the bar with the saddle F is continued. On the other hand, when the roll i^8 in the outer free end of the arm i^7 is resting upon one of the high pattern-surfaces s then the longer stops i^{13} will be brought into line with the bar I^4 and the stops i^{11} and i^{12} carried to one side thereof, as shown in Fig. 17. In these positions the stop i^{13} will contact with the end of the bar I^4 when the bar is reciprocated toward it, and as a consequence of its greater length it will move the bar the length of the slots i^2 and i^3 and of their respective extended portions i^5 and i^6 , with the result of carrying both of the advancing-cams into inoperative positions, as shown in Fig. 9. The cams having been carried into these positions will be retained in them as long as the roll i^8 is resting upon the high pattern-surface s ; but immediately this high pattern-surface passes from under that roll the stops i^{11} and i^{12} will through the action of a retracting-spring i^{14} be brought into line with the bar I^4 , which at its next reciprocation with the saddle F will contact at its end with the stop i^{11} and be thereby moved into the position shown in Fig. 8, with the consequent effect of returning the cams into operation and permitting of their subsequent actuation by the stops i^{11} and i^{12} , as before explained. Thus through the mechanism described the control of the bar I^4 is effected from the pattern-chain S^4 and the advancing-cam of the needles of the rear needle-bar not only brought into operation and properly actuated when the knitting of the body of the article or fabric is being effected, but carried out of operation and there-

held when the knitting of a welt is being accomplished. The pattern-chain S^3 is in like manner employed for controlling the movements of the bar H^2 , by means of which the adjustment of the retracting-cam I^2 of the needles of the front needle-bar upward and downward transversely of its carrying-plate is accomplished to shorten or lengthen the loops that are being produced. In order to render it capable of accomplishing this result, the shaft H^3 is made use of, which, like the shaft I^5 , is journaled in the stands A^2 and A^3 and which in addition to an arm h^{15} , that rests at its outer free end on the pattern-chain through the medium of a roll h^{16} , is equipped near its opposite ends with two upwardly-extending arms h^{17} and h^{18} , that respectively carry at their upper ends the stops h^{19} and h^{20} . These stops, like the stops i^{11} , i^{12} , and i^{13} , are preferably constructed in the form of inwardly-projecting pins and coöperate with the bar H^2 , which is moved longitudinally in one or the other directions therefrom as it is carried back and forth by the saddle F in the operation of the machine. In order, therefore, to permit of this bar H^2 being moved from that source and when so moved in one or the other directions left during a number of reciprocations of the saddle F without disturbance, the stops h^{19} and h^{20} instead of being arranged in line are so disposed with respect to each other and to the bar that when one is brought into line with it the other is carried to one side thereof, and vice versa, as shown in Fig. 16. As thus related when the low pattern-surface s' is passed beneath the roll h^{16} in the outer free end of the arm h^{15} the stop h^{20} will be brought into line with the bar, as shown by dotted lines in that figure, and the stop h^{19} carried to one side thereof, the result of which will be that when the bar is reciprocated by the saddle F it will be brought into contact at its end with the former stop and moved into the position shown in Figs. 1, 2, and 5, thereby raising through the crank-arm h^{12} , the shaft h^9 , and crank or eccentric h^6 the retracting-cam I^2 , with the consequent effect of shortening the lengths of the loops being knit. On the other hand, when the high pattern-surface s is carried beneath the roll h^{16} then the stop h^{19} will be moved into line with the bar H^2 , as shown by full lines in Fig. 16, and the stop h^{20} carried to the opposite side thereof, in which positions the former stop will be struck by the bar H^2 and such bar moved thereby into the position shown by dotted lines in Fig. 5 as it is reciprocated toward it with the saddle F, the crank or eccentric h^6 thereby rotated through the crank-arm h^{12} and shaft h^9 , and the retracting-cam I^2 thereupon moved downward, with the result of lengthening the loops, and so on, the movements of the retracting-cam to accomplish this shortening and lengthening effect being thus determined by the low and high pattern-surfaces upon the pattern-chains S^3 and by

a coöperating spring h^{21} , which, coiled around the shaft H^3 , is connected at one end thereto and at the other to the stand A^2 or other convenient part. While the upwardly-extending arms h^{17} and h^{18} are thus employed for supporting the stops h^{19} and h^{20} , by means of which the bar H^2 is operated, they are also availed of to support the respective stops h^{22} and h^{23} , through which the bar I^3 , that coöperates with the advancing-cams I and I' of the needles of the front needle-bar D , is moved longitudinally in one and then in the other direction as it is reciprocated back and forth with the saddle in the operation of the machine to bring one and then the other of these cams into and then carry them out of operation in the same order, accordingly as one or the other of them is to lead and the other to follow. As thus supported these stops, which are preferably constructed in the form of inwardly-projecting pins, are so disposed as to bring them into axial coincidence and into line with the bar I^3 , whereby to be struck by the respective ends of the latter as it is reciprocated back and forth between them. When the roll h^{16} in the outer free end of the arm h^{15} is resting upon the low pattern-surface s' , these stops will contact with the ends of the bar near its under side. On the other hand, when this roll is resting upon one of the high pattern-surfaces s then these stops will contact with its ends near its upper side; but into whatever position they may be moved by the pattern-chain one and then the other of these stops will be invariably brought into contact with its respective end of the bar and such bar thereby moved to the required extent as it is reciprocated back and forth between them, as shown in Fig. 16. The pattern-chain S , on the other hand, is availed of for controlling the movements of the bar K^2 , by means of which the lowering and raising of the withdrawing-cam K of the needles of the rear needle-bar D' are effected, while the pattern-chain S' is similarly employed for controlling the movements of the bar K' , through which corresponding depression and elevation of the withdrawing-cam K of the needles of the front needle-bar D are likewise accomplished. To permit of the control of these movements from those sources, the shafts K^3 and K^4 are made use of, of which the shaft K^4 is employed in connection with the pattern-chain S and bar K^2 , while the shaft K^3 is similarly employed in connection with the pattern-chain S' and bar K' . As thus employed these shafts are journaled in the stands A^2 and A^3 , and along with an arm k^7 , that rests at its outer free end upon its respective pattern-chain S or S' through the intervention of a roll k^8 , they are each equipped near its opposite extremities with upwardly-extending arms k^9 and k^{10} , which respectively support at their upper ends inwardly-extending pin-like stops k^{11} and k^{12} for coöperating with their appropriate bar K^2 or K^3 and moving the same

longitudinally in one or the other direction as it is brought against them in the operation of the machine. In order, therefore, to permit of these bars being thus moved from those devices and when so moved in one or the other directions left during a number of reciprocations of the saddle F without disturbance, the stops k^{11} and k^{12} appropriate to each of the shafts K^3 and K^4 instead of being arranged in line are so disposed with respect to each other and to their respective bar K' or K^2 that when one is brought into line with it the other is carried to one side of the same, and vice versa, as shown in Fig. 15. As thus arranged whenever the low pattern-surface s' of either of the pattern-chains S or S' is passed beneath its coöperating roll k^8 the stop k^{11} answering thereto will be brought into line with its respective bar, as shown by dotted lines in that figure, and its coöperating stop k^{12} carried to one side thereof, the result of which will be that when the bar is reciprocated by the saddle F it will be brought into contact at its end with the former stop and moved into the position shown in Fig. 2, with the effect of raising, through the slot-and-pin connection k^4 and k^5 , its respective withdrawing-cam from operation. In the position to which the bar is thus moved it will be retained as long as the low pattern-surface s remains under the roll k^8 ; but immediately a high pattern-surface s is substituted therefor, as when the narrowing operation is to be performed, the stop k^{12} will be moved into line with the bar, as shown by full lines in such figure, and the stop k^{11} carried to one side thereof, when in its next reciprocation the bar will strike the former stop and be moved thereby into the position shown in Fig. 1, in which through the pin-and-slot connection above described its coöperating withdrawing-cam will be forced downward into position for engagement with the butts d^8 of its respective needles as it is carried over them, as illustrated in Fig. 12. Having been thus forced downward into this position, it will be retained therein as long as the high pattern-surface s is beneath its roll k^8 ; but immediately it is removed therefrom the stop k^{11} will through the action of an appropriate retracing-spring k^3 , with which each of the shafts K^3 and K^4 is provided, be brought opposite its appropriate bar K' or K^2 , which will then be moved in an opposite direction at its next reciprocation toward it with the saddle F and its appropriate withdrawing-cam thereby raised into an inoperative position, and so on, the longitudinal backward and forward movements of these bars K^2 and K^3 being thus determined by the high and low pattern-surfaces on their respective pattern-chains, and their coöperating withdrawing-cams thereby raised and lowered, as the requirements of the article or fabric being produced may demand. Similarly the pattern-chains S^5 and S^6 are made use of for controlling the movements of the needle-elevators L , whereby their respective needles are brought into op-

eration to effect the widening of the article or fabric being produced at the required places, the chain S^5 being employed in connection with the elevator of the needles of the front needle-bar D and the chain S^6 being in like manner employed in connection with the elevator of the needles of the rear needle-bar D'. To enable these chains to accomplish the results thus specified, the shafts L^2 and L^3 are made use of, which are rotatively mounted in the stands A^2 and A^3 below and outside of the needle-bars, respectively, and are severally provided with outwardly-extending arms l^{13} , (see Fig. 2,) that are jointed at their outer free ends to the outer free ends of corresponding levers l^{14} , which, respectively mounted upon the shafts K^3 and K^4 , so as to oscillate upon them, are severally provided in their inner ends with rolls l^{16} , which rest upon their appropriate pattern-chains. As thus arranged and equipped these shafts L^2 and L^3 are each provided at the proper distance apart with a number of outwardly and upwardly extending arms l^{17} , that support and carry at or near their outer free ends in parallel relationship to their respective shafts a rod l^{18} , which coöperates with its appropriate needle-elevator through the intervention of a sliding connecting-bar l^{19} , that is fitted to slide in a suitable guideway l^{20} , formed in the saddle F to receive it. In their normal positions these elevators L are held with their free ends raised above the butts d^8 of the needles that are to be carried into operation to effect the widening of the article or fabric by the mechanism above described, as shown in Figs. 4 and 6, and in these positions the rolls l^{16} rest upon the low surface s' of their respective pattern-chains. On the other hand, when they are to be lowered to bring them into operative positions then the high surfaces s on their appropriate pattern-chains are passed beneath the rolls l^{16} , carrying the rods l^{18} in directions away from their respective elevators and allowing the latter to be carried downward into their operative positions, as shown in Figs. 7 and 12, in which they will be held by their respective springs l^7 until these high surfaces on the pattern-chains are carried from under their coöperating rolls l^{16} , when they will be again raised and carried out of operation, and so on, the high and low surfaces on the respective pattern-chains thus determining when the elevators shall be brought into and carried out of operation. The shafts L^2 and L^3 , with the parts connected with them, being thus moved in one direction by the high surfaces s on their respective pattern-chains are returned in the other direction when these high surfaces are removed from under the rolls l^{16} by the action of weighted arms l^{21} or suitably-formed springs, as preferred. With the needle-elevators connected with their respective coöperative pattern-chains, as above explained, not only are the movements of the former into and out of operation controlled by the latter,

but in consequence of the sliding connection between them and their respective coöperating rods l^{18} they are yet left free to slide back and forth with the needle-operating cams without the operating continuity of the mechanism between them and their pattern-chains being broken at any time. While the pattern-chains S^4 , S^3 , S , S' , S^5 , and S^6 are thus employed for the purposes above explained, the pattern-chain S^2 is utilized to control the movements of the yarn-carriers N N as the exigencies of the pattern being produced or materials employed may require. To this end the switch N' is made use of, which, provided in its face with a longitudinally-disposed tapering groove n^6 for engagement with the laterally-projecting arm o' of the locking-lever O, is fixedly secured to a shaft N^2 , that is rotatively mounted in the stands M M and is oscillated in one direction by the pattern-chain S^2 and in the other by a coöperating retracting-spring n^7 . To permit of this being accomplished a lever n^8 is employed, which, loosely fulcrumed upon the shaft and provided on its inner end with a roll n^9 for engagement with the pattern-chain, is jointed at its outer end to the lower extremity of a connecting-rod n^{10} , which is jointed at its upper extremity to the outer end of an arm n^{11} , that is fixedly secured to the shaft, while the retracting-spring is preferably coiled about the shaft N^2 and connected at one end thereto and is connected at its other to the stand M. By this arrangement, as will be seen, the movements of oscillation of the shaft are determined by the pattern-chain S^2 , and when it is oscillated to the limit of its movements in one direction, as will be the case when one of the high surfaces s on the pattern-chain is passed beneath the roll n^9 , the outer end of the laterally-projecting arm o' in passing through the groove n^6 in its travel with the saddle F will tilt the locking-bar O on its pivot o^2 and carry its upwardly-extending arm o out of engagement with the recess o^3 in the stud O' of one of the yarn-carriers and into the recess o^3 of the stud O' of the other. On the other hand, when the shaft N^2 is oscillated to the limit of its movement in the opposite direction, as will be the case when a low surface s' on the pattern-chain is carried beneath the roll n^9 , then the outer end of the laterally-projecting arm o' in passing through such groove will tilt the locking-bar O on its pivot in the opposite direction, with the consequent effect of disengaging its upwardly-extending arm o from the recess o^3 of the last and carrying it into engagement with the recess o^3 of the stud O' of the first mentioned carrier and so on, the particular carrier to be brought into operation and the length of time it is to remain therein being thus determined by the pattern-chains.

It will thus be seen that through the mechanism described the various adjustments of the needle-operating cams and the carrying of the needle-elevators and yarn-guides into and out of action are all effected from appropriate

pattern-chains and a machine produced in which not only may ornamented fashioned articles of various forms be produced in succession and in continuous chains, but the several operations of forming welts therein, of widening and narrowing them at the required places, and of ornamenting the same, necessary to their production, be automatically accomplished in the required order.

10 While in the foregoing I have described the form of my invention which I prefer to employ in practice, I wish it distinctly understood that I do not limit myself strictly thereto, as it is obvious that such form is merely illustrative and may be changed and modified in various ways without departing from the spirit thereof—as, for instance, instead of employing the extensions i^5 and i^6 in connection with the respective slots i^2 and i^3 of the bar I^4 15 alone I may, if I so desire, also employ them in connection with the respective but reversely-arranged slots i^2 and i^3 of the front sliding bar I^3 , in which case the needles of the front needle-bar may be rendered inactive and 20 the needles of the rear needle-bar rendered active when the saddle F is reciprocated in one direction and reversely when reciprocated in the opposite direction to produce a tubular fabric, as is common to the knitting-machines 25 of the Lamb class, by substituting a longer stop in place of the present stop h^{22} in the arm h^{17} , whereby it may operate upon the sliding bar I^3 as the stop i^{13} operates upon the sliding bar I^4 and so disposing the respective high 30 and low pattern-surfaces s and s' upon the pattern-chains S^4 and S^3 that the longer stops i^{13} and h^{22} , as well as the shorter stops i^{11} and h^{23} , shall be brought into line with their respective sliding bars I^4 and I^3 as these bars 35 are reciprocated toward the one or the other in the operation of the machine. In like manner instead of constructing the reversely-arranged diagonal portions of the slots i^2 and i^3 straight or rectilinear I may, if I so desire, 40 provide them with short longitudinally-disposed middle portions i^* , as shown in Fig. 19, in which case I may produce what is known as "tuckwork" by respectively equipping the appropriate stop-carrying arms, as i^9 and 45 i^{10} , with suitable stops i^{30} and i^{**} of the proper lengths and so disposing the high and low pattern-surfaces s and s' of the coöperating pattern-chain S^3 or S^4 as to alternately bring these stops, with the stops i^{11} and i^{12} or h^{22} and h^{23} , 50 as the case may be, into line with their appropriate sliding bar I^3 or I^4 to be struck by it as it is carried back and forth with the saddle F in the operation of the machine. By these means when the stops i^{30} and i^{**} are 55 brought into action upon their coöperating sliding bar I^3 or I^4 and the movement of such bar thereby limited to the distance between the lowermost portions of the slots i^2 and i^3 and the longitudinally-disposed middle portion i^* the leading advancing-cam I or I' will 60 be swung from its inoperative toward its operative position only sufficiently far to cause 65

its coöperating needles to be advanced only the required distance to engage the yarn to form new loops without causing the old loops carried by them to slide below their respective latches, while when the stops i^{11} and i^{12} or h^{22} and h^{23} are brought into action upon such bar its movement will extend from the lowermost to the uppermost portion of those slots i^2 and i^3 and the normal movements of the needles and knitting operation be thereby effected, all as is common to knitting-machines when this character of "work" is being produced.

Having now described my invention and specified certain of the ways in which it is or may be carried into effect, I claim and desire to secure by Letters Patent of the United States—

1. The combination, with the needles of a knitting-machine, a support for these needles, a cam-carrier, and a retracting-cam carried thereby and stationarily supported with respect thereto, of pivoted advancing-cams arranged on opposite sides of the retracting-cam, and means independent of the needles whereby one and then the other of these advancing-cams may be automatically swung upwardly into, and downwardly out of, operative position as the carrier is moved in one and the other direction, and be positively held in those positions, substantially as described.

2. The combination, with the advancing-cams, a reciprocating carrier in which such cams are pivoted, and crank-arms secured to the pivots of such cams and provided with projecting pins, of a sliding bar provided with slots for engaging with such pins constructed with oppositely-disposed diagonal middle portions and longitudinally-extending ends, whereby as said sliding bar is moved longitudinally back and forth first one and then the other of these cams will be brought into and carried out of operative position and be positively held in the positions to which they may be thus brought and carried, substantially as described.

3. The combination, with a reciprocating carrier, a plurality of advancing-cams pivoted in it, crank-arms secured to the ends of the cam-pivots and provided with outwardly-projecting pins, and a sliding bar provided with slots for engaging with such pins constructed with oppositely-disposed diagonal middle portions and longitudinally-extending ends, of stops with which the opposite ends of the sliding bar contact as it is carried back and forth with the reciprocating carrier and is moved longitudinally thereby, substantially as described.

4. The combination, with a reciprocating carrier, and a plurality of advancing-cams pivoted to it, crank-arms secured to the cam-pivots and provided with projecting pins, of a sliding bar provided with slots i^2 and i^3 for engagement with such pins constructed with oppositely-disposed diagonal middle portions

and longitudinally-extending ends and also with extended portions i^5 and i^6 respectively, stops of different lengths for moving the sliding bar when its ends are brought into contact with them in its travel with the reciprocating carrier, and pattern devices by which either the shorter or the longer stops may be brought into line with such sliding bar, as said cams are to be operated or withdrawn into inoperative positions, substantially as described.

5. The combination with the reciprocating saddle F, the cam-carrying plate H, the advancing-cams I and I', the shafts i upon which these cams are supported, and the crank-arms i' secured to such shafts and provided with pins i^4 , of the sliding bar I³ provided with the slots i^2 and i^3 having longitudinally-extending ends for engagement with such 15 pins, stops h^{22} and h^{23} , and supports for these stops whereby such advancing-cams are not only carried and operated, but positively locked at the limits of their respective movements, substantially as described.

25. 6. The combination, with the reciprocating saddle F, the cam-carrying plate H', the advancing-cams I and I', the shafts i upon which these cams are supported, the crank-arms i' secured to such shafts and provided with pins i^4 , of the sliding bar I⁴ provided with slots i^2 and i^3 for engagement with such pins and constructed with the extended portions i^5 and i^6 respectively, stops i^{11} , i^{12} , and i^{13} , a pattern-chain and intermediate devices by means of 30 which either the stops i^{11} and i^{12} or the stop i^{13} may be brought into line with the bar I to contact with its ends to move such bar as it is carried against them or it in its reciprocation with the saddle, as said cams are to be 35 operated or carried out of operation, substantially as described.

7. The combination, with the reciprocating saddle, the cam-carrying plate H' secured thereto, the pivoted advancing-cams I and I', the sliding bar I⁴, the devices through which the advancing-cams are connected with the sliding bar and the pattern-surface S⁴, of the shaft I⁵ provided with the arm i^7 for resting upon the pattern-surfaces, and the arms i^9 and i^{10} , the former of which is provided with a stop i^{11} , and the latter of which is equipped with the two stops i^{12} and i^{13} of different lengths, the shorter stop i^{12} being disposed in line with the stop i^{11} , and the longer stop i^{13} 40 arranged to one side thereof, substantially as described.

8. The combination, with the reciprocating saddle F, and the cam-carrying plate H provided with the needle-advancing cams and 45 with transversely-arranged guideways h^2 , of the carrier h' fitted to slide in such guideways and provided with a slot h^5 , the retracting-cam I² mounted upon such carrier, the crank or eccentric h^6 engaging with said slot, the 50 shaft h^9 , the crank-arm h^{12} , the bar H², the stops h^{19} and h^{20} , and means whereby one or the other of these stops may be brought into

line with the bar H² to move the same in one or the other directions as it is carried against such stop in its reciprocation with the saddle 70 F, and thereby move the carrier h' and with it the retracting-cam I² in one or the other directions across the cam-carrying plate, substantially as described.

9. The combination, with the reciprocating saddle F, the cam-carrying plate H, the retracting-cam I² and pivoted advancing-cams I and I' carried by such cam-carrying plate, the bars H² and I³, devices by which the retracting-cam and the advancing-cams are respectively connected with said bars, and a pattern-surface S³, of a shaft H³, an arm h^{15} for resting upon the pattern-surface, and arms h^{17} and h^{18} which are respectively provided with the stops h^{19} , h^{22} , and h^{20} and h^{23} , 85 substantially as described.

10. The combination, with the needles of a knitting-machine provided with butts d^2 and d^8 , the support for such needles, the reciprocating saddle, advancing and retracting cams 90 for coöperating with the butts d^2 of these needles, and a carrying-plate for supporting and carrying said cams, provided with a flattened V-shaped orifice, of a needle-elevator pivoted to the upper side of the cam-carrying 95 plate and extending through the V-shaped orifice, for engagement with the butts d^8 of the needles, and guiding-ledges arranged on opposite sides of the V-shaped orifice and constructed with inclined upper surfaces on 100 their inner ends to engage with and carry upward the needles raised by the elevator, substantially as described.

11. The combination, with the needles of a knitting-machine having butts d^2 and d^8 , a 105 support for such needles, the needle advancing and retracting cams for coöperating with the butts d^2 , of a withdrawing-cam located below such advancing and retracting cams, and adapted to be carried forward toward 110 and backward from such needles to engage it with and disengage it from the butts d^8 of such needles as these needles are to be respectively withdrawn from or continued in 115 operation, substantially as described.

12. The combination, with the needles of a knitting-machine having butts d^2 and d^8 , a bed in which such needles are held and reciprocated, a reciprocating cam-carrying plate, provided with needle-supporting ledges, 120 and needle advancing and retracting cams carried by such plate for coöperation with the butts d^2 , of a needle-withdrawing cam carried by said cam-carrying plate for coöperation with the butts d^8 and located between the inner 125 ends of the needle-supporting ledges directly below such advancing and retracting cams, and mechanism by which such withdrawing-cam is automatically carried inward toward and backward from such needles to engage 130 it with and disengage it from the butts d^8 thereof as such needles are to be respectively withdrawn from or continued in operation, substantially as described.

13. The combination, with a cam-carrying plate and means by which it is reciprocated, of a needle-withdrawing cam, a carrying-bar for such cam fitted to slide transversely through said carrying-plate and provided on its side with a projection, a bar fitted to slide transversely of this carrying-bar and provided with a slot for engaging with such projection and constructed with a diagonally-arranged middle portion with longitudinally-extending ends, and means for sliding this bar in one and the other direction whereby the said cam may be respectively protruded from, and withdrawn toward, the cam-carrying plate, substantially as described.

14. The combination, with a needle-bed, needles d' arranged to be reciprocated therein and provided with butts d^2 and d^3 , a reciprocating saddle F, a cam-carrying plate secured to and traveling with such saddle, and needle advancing and retracting cams for cooperating with the butts d^2 carried by such

carrying-plate, of a needle-withdrawing cam K arranged below and in relation to the retracting-cam for coöperation with the butts d^2 , a carrying-bar k' for said withdrawing-cam fitted to slide transversely through the cam-carrying plate and provided on its side with a projection k^5 , a bar arranged to slide back and forth transversely of said carrying-bar k' , and provided with a slot k^4 for engagement with such projection k^5 and constructed with an inclined middle portion and longitudinally-extending ends, and a pattern-surface and intermediate mechanism through which the back-and-forth movements of the slotted bar may be automatically controlled, substantially as described.

In witness whereof I have hereunto set my hand this 23d day of November, 1900.

WILLIAM S. MILLS.
